COLOSTOMY POUCH APPARATUS

Isaiah F. Spindell, Lynn, Mass.

Application December 18, 1934, Serial No. 758,062

3 Claims. (Cl. 128—283)

My invention relates to surgical appliances and to colostomy pouch apparatuses in particular, and it has for its object to provide an improved apparatus of this class.

5 An objectionable feature characterizing devices of this class as heretofore constructed has resided in the construction and operation of the waistband for holding the pouch in position on and against the wearer's body.

10 Sometimes the waistband has been made longitudinally elastic and sometimes non-elastic. Also, it is old to construct the waistband with a single body-encircling strap, or with two straps disposed edge-to-edge throughout their lengths or 15 separated so that one could occupy a position above and the other below the hips at opposite sides of the body.

Difficulty has been experienced, however, in 20 providing a waistband which would yieldingly and securely hold the pouch snugly in a fixed position against the wearer's body in all positions of the latter, and most of the constructions heretofore proposed have not been fully satisfactory in this respect so far as I know. 25 My invention has for its main object to provide a waistband structure which will be more efficient than those heretofore proposed and which will serve to hold the pouch yieldingly and snugly against the wearer's body in all positions of the latter as while standing and while lying down.

To these ends I have provided an improved colostomy pouch apparatus or outfit having the peculiar features of construction set forth in the following description, the several novel features 35 of the invention being separately pointed out and defined in the claims at the close thereof.

In the accompanying drawings:—

Figure 1 is a front elevation, partly broken away, of a colostomy pouch showing the opposite end portions of my improved waistband attached thereto.

Figure 2 is a side elevation of a portion of a human body having applied thereto a colostomy pouch apparatus constructed in accordance with 45 my invention.

Figure 3 is a front elevation of one end portion of my improved waistband and

Figure 4 is a front elevation of the opposite end portion of the waistband, said two figures 50 showing the latter in its entirety.

The main feature of novelty of my invention resides in the construction of the waistband and the illustrated embodiment thereof comprises two webs or straps 10 and 11 each of which is a 55 woven textile fabric having elastic rubber warp

threads incorporated therein throughout its width in the usual manner so that the web is longitudinally elastic and transversely non-elastic.

For a portion of their lengths and mid-way 5 between their opposite ends the two webs are disposed relatively parallel and have their proximate marginal portions overlapped as shown in Figs. 3 and 4.

The middle portions of the webs are fixed in 10 their relatively overlapped positions by transverse strips or tapes 12, one at each end thereof, and constitute the middle section A of the body of the waistband which latter also includes two opposite end sections B each consisting of the two 15 proximate end portions of the webs.

The marginal portions of each strip 12 are fastened to the webs by lines through-and-through stitching which define a pocket beneath said strip within which is confined a transversely 20 disposed flexible stay 14 and which also fasten the overlapped portions of the webs together.

From each transverse strip 12 the proximate end portions of the webs extend convergingly for a substantial distance to provide an end section 25 B, and have their extremities superposed and approximately registered one with the other. Extending transversely across the end of the outermost web 10 is a reinforcing strip or tape 15 which is fastened in position thereon by 30 through-and-through stitching 16 which also serves to secure the ends of the webs together.

Between the strip 15 and web 10 of the body section B are disposed proximate ends of a pair of parallel straps 17 whose opposite ends are permanently equipped with metal eyes 18. Adjacent to the eyes 18 is a transversely disposed reinforcing tie in the form of a strip or tape 19 whose opposite end portions are secured to said straps by through-and-through stitching 40 20. This stitching also secures one end of a textile shield extension 21 to the straps 17, said shield being for use between the eyes 18 and the body of the wearer when the waistband is in position upon the latter.

Between the strip 15 and web 10 of the opposite body section B are disposed proximate ends of another pair of parallel straps 22 on each of which is adjustably mounted a hook member 23 to co-operate with one of the eyes 18.

The hook members 23 are independently adjustable so that the effective length of each strap 22 may be varied to suit the requirements imposed by the shape of the wearer's body, and it will also be clear that when the waistband is 55

- in position on the body one of these straps may be positioned above the hip at one side of the body and the other below so that displacement of the straps relatively to the body is prevented.
- 5 If the waistband extends around and over the hip at the opposite side of the body, it will be clear that the longitudinal elasticity of the body of the band will permit the latter to conform to the shape of the wearer's body.
- 10 The straps 17 are provided to interlock with and press against the usual wire frame or cage 23 within which the usual rubber pouch 24 is confined. That is to say, the straps 17 extend around the outside of the cage 23 and occupy positions behind arms or lugs 25 provided on the frame of cage 23, said arms or lugs being part of a horizontal crossbar or wire 28 which is engaged by the strap so as to hold the pouch frame against displacement vertically relatively to the 15 waistband, said straps 17 providing a narrow slit between them through which a part of the frame of the pouch is buttoned.

The apparatus is applied to the body of the wearer by extending the waistband around said body with the inlet of the pouch in register with and surrounding the opening in the wearer's body and after adjustment thereof the hook members 23 are engaged with the eyes 18. The body portion A—B of the waistband is not only longitudinally elastic and elastically conformable to the shape of the body but the overlapping portions of the waistband webs between the strips 12 and also between the strips 12 and 15 are not stitched or otherwise joined together so that said intermediate portions of the two webs which are opposite each other are free to adjust themselves relatively thereby further increasing the capacity of the waistband to fit itself to the body.

What I claim is:

- 40 1. A colostomy pouch apparatus having, in combination, a pouch-supporting wire cage for removably holding a pouch in position against the body of the wearer, and a waistband consisting of two longitudinally elastic webs of equal length disposed side by side in overlapped relationship 45 throughout their lengths with their intermedi-

ate back-engaging portions disposed relatively parallel and partially overlapped and with opposite pairs of proximate end portions of said webs converging toward each other and having their extremities disposed in superposed relation, a 5 transverse stay at the junction of each pair of converging end portions with said parallel intermediate portions and fastened to both of said webs so as to maintain the intermediate portions of the latter normally parallel and partially overlapped, means fastening the extremities of each pair of end portions in superposed relation, and means for separably attaching the opposite superposed ends of the webs to said pouch-supporting wire frame.

2. As a new article of manufacture, a waistband for removably supporting a wire pouch-holding frame, said waistband comprising two longitudinally elastic webs of equal lengths disposed side by side in overlapped relationship 20 throughout their lengths with two independently elastic intermediate back-engaging portions of said webs disposed parallel to each other and partially overlapped and with opposite pairs of proximate end portions of said webs converging 25 toward each other and having their extremities disposed in superposed relation, a transversely disposed endwise stiff and laterally flexible stay at the junction of each pair of converging end portions with said parallel intermediate portions 30 and fastened to said webs so as to maintain the intermediate portions of the latter normally parallel and partially overlapped, means fastening the extremities of each pair of end portions in superposed relation, and strap means for separably and adjustably connecting the opposite superposed ends of the webs together and for 35 separably supporting said wire frame.

3. As a new article of manufacture, a waistband constructed in accordance with claim 2 40 wherein said last-mentioned strap means comprises two parallel straps disposed edge to edge and providing between them a slit through which a part of said frame is removably buttoned to secure the latter to the waistband.

ISAIAH F. SPINDELL. 45
